AIR-SPACE INSULATED CONDUCTOR

Theodor Lehne, Dallgow-Doberitz, Kreis Ost-Havelland, Konrad Schluckebier, Berlin-Siemensstadt, Paul Thomas, Berlin-Wilmersdorf, and Hans Wassmannsdorff, Berlin-Spandau, Germany, assignors to Siemens & Halske Aktiengesellschaft, Siemensstadt, near Berlin, Germany, a corporation of Germany

Application March 18, 1938, Serial No. 196,664
In Germany April 28, 1938

7 Claims. (CL 174—29)

This invention relates to air-space insulated conductors having at least one spacer consisting of resistant insulating material and wound in open helical turns around the conductor and 5 a screen or outer conductor arranged over the air-space insulation, and has for its object to attain a very small capacity and therefore a low line attenuation.

In order to form the air-space insulation in 10 the case of air-space insulated conductors it has hitherto been customary to wind one or more continuous spacers firmly around the conductor so as to ensure with the aid of the spacers also an accurate centering of the conductor within 15 the sleeve surrounding the same. In such air-space insulated conductors the capacity is the smaller, the greater the pitch of the spacers wound around the conductor. However, the capacity may also be reduced by employing 20 spacers in the form of multiple cores, helices and the like.

According to the invention the capacity of air-space insulated conductors, having at least one spacer consisting of mechanically resistant insulating material—i. e. solid insulating material which retains its form and resists compression—25 wound in open helical turns around the conductor and a screen or an outer conductor or conducting sheath, is reduced to a further extent 30 by rendering self-supporting each cylindrical spacer winding wound around the conductor in spaced relation thereto and by making the inner diameter of the spacer winding at least 50% greater than the outside diameter of the conductor. 35

The self-supporting spacer winding is obtained in the manner that the spacer is made of mechanically resistant insulating substances and by the fact that a sufficiently small pitch is chosen 40 for the spacer wound around the conductor. By correspondingly dimensioning the spacer winding, the latter may be made without difficulties sufficiently resistant to compression for all operating conditions. Since the spacer winding is so 45 designed as to be self-supporting the air-space insulation designed according to the invention presents a relatively high resistance to mechanical stresses. The loose arrangement of the conductor within the spacer winding has 50 from a mechanical point of view the further advantage that the conductor is sufficiently free to move in the case of longitudinal changes caused by the fluctuations of temperature without 55 damaging the spacer. The extremely small capacity is obtained by the fact that the spacer

winding just touches the conductor at intervals. The distance of the points at which the spacer winding comes into contact with the conductor may be still increased by slightly corrugating the conductor, not enough, however, to impair the electric properties of transmission. The eccentricity of the inner conductor present at certain spaced points in the case of the air-space insulation according to the invention is practically without any importance, since over 10 the air-space insulation is arranged a screen or return conductor by means of which the conditions of capacity are defined to a great extent.

It is also possible according to the invention to build up the air-space insulation of the conductor of a plurality, preferably of two spacer layers, only the inner spacer layer being designed according to the invention. This has the advantage that the inner spacer winding may be made of a relatively thin thread so that on the 15 one hand the manufacture of the air-space insulated conductor is facilitated and on the other hand the capacity thereof is rendered smaller.

Cellulose derivatives or suitable insulating substances of the group of the polyvinyl compounds, 20 for instance, polystyrene are preferably employed as mechanically resistant insulating substances for the spacer windings. In case the air-space insulated conductor is employed in high-frequency cables the use of flexible polystyrene threads is 25 preferable which are rendered flexible in the plastic state of the material by suitable well-known stretching methods.

If the air-space insulated conductor is to be used as a highly flexible conductor the protective 30 sleeves arranged over the self-supporting air-space insulation are designed in the form of highly flexible sleeves. Highly flexible screens in the form of metallic foil windings, wire meshes, etc., and furthermore coverings of fibrous materials are employed for this purpose. A preferable form of the invention consists in manufacturing the protective sleeve arranged over the 35 screen or outer conductor from rubber or rubber-like artificial substances and in metallizing the 40 same preferably with pulverized aluminum. It may also be advantageous to arrange one or more insulating and in some cases water-proof protective layers not only over the screen but also 45 underneath the same. Such highly flexible conductors are employed to advantage as downleads for aerial systems.

In the accompanying drawing are diagrammatically shown various forms of the invention. In these drawings—

Fig. 1 represents a high-frequency concentric air spaced cable having one spacer thread of solid insulating material wound around the inner conductor.

5 Fig. 2 represents a similar cable, in which around the spacer thread an additional thinner spacer thread is wound.

Fig. 3 represents a cable in which the entire air space insulation is divided into two separate 10 spacer layers.

Fig. 4 represents a cable with a relatively thin inner conductor, a self-supporting spacer winding of large diameter, and a braided outer conductor.

15 Fig. 5 represents a cable similar to that of Fig. 4, having a double spacer winding placed around the inner conductor, and

Figs. 6 and 7 show an insulation sleeve arranged between the air spacing helix and the braided outer conductor.

20 Fig. 1 shows a concentric high-frequency cable according to the invention. Around the inner conductor 10 is wound in open helical turns the solid thread 11 of circular cross-section consisting of resistant insulating materials, for instance, of polystyrene; however, in contradistinction to the known types of inner conductors in such a manner as to obtain by selecting a small pitch a self-supporting spacer winding which is 25 resistant to compression within certain limits and whose inner diameter is by more than 50% greater than the diameter of the conductor 10. The spacer winding is surrounded by a closed band winding 12 of insulating material. The outer conductor 13 consisting of good conducting band segments, the open band winding 14, the closed band winding 15 of insulating material and the water-tight cable sheath 16 are arranged successively around the closed band winding 12. Since the thread 11 used for the 30 spacer winding should not exceed a predetermined thickness this type of air-space insulation is particularly employed in concentric cables of very small cross-section; i. e., in cables with relatively great line attenuation.

45 According to Fig. 2, the spacer 21, consisting of a centrally arranged thread 22 and of the thread 23 wound around the latter in open helical turns, is wound around the inner conductor 20 in open helical turns. The spacer 21 is wound 50 as an open spacer winding in a manner so as to be self-supporting, and is so spaced from the conductor 20 that the inner diameter of the spacer winding 21 is at least 50% greater than the diameter of the conductor 20. The threads 55 22 and 23 consist preferably of polystyrene. The thread 22 may be a single or a multiple thread; for instance, a cord consisting of several thin strands. The closed band winding 24 of insulating material, the return conductor 25 consisting 60 of good conducting band segments, the open band winding 26 serving to hold together the outer conductor bands, the closed band winding 27 of insulating material and the water-proof cable sheath 28 are arranged in respective succession over the spacer winding 21.

Fig. 3 shows an embodiment in which the entire air-space insulation of the conductor is subdivided into two spacer layers. Around the inner conductor 30 is first wound the spacer winding 31 consisting of a thread and whose inner diameter is according to the invention greater than that of the conductor. By the use of suitable insulating material and by suitably dimensioning the spacer winding the latter becomes 70 self-supporting and sufficiently resistant to com-

pression so that further layers of insulation may be arranged around the spacer winding. According to the embodiment shown in Fig. 3 a closed band winding 32 consisting of insulating material is first wound around the spacer winding 31. The second spacer layer is formed of the spacer 33 wound in open helical turns over which is arranged a closed band winding 34 of insulating material. When using the cable for high-frequency transmission the spacers 31 and 33 as 10 well as the band windings 32 and 34 are preferably made of high-grade insulating material suitable for high-frequency such as, for instance, polystyrene. The spacer 33 in the present case is made in the form of a cord consisting of such 15 insulating material; however, it may also be made in another known manner; for instance, in the form of a thread helix consisting of mechanically 20 resistant insulating material. Over the band winding 34 are arranged first the outer conductor 35, then the open band winding 36, the closed band winding 37 of insulating material and lastly the water-proof cable sheath 38.

Figs. 4 to 7 show further embodiments of the 25 invention which are employed for flexible air-space insulated conductors, for instance, for aerials.

According to Fig. 4 the relatively thin conductor 40 is surrounded with the self-supporting 30 spacer winding 41 made of mechanically resistant insulating materials and whose inner diameter is preferably many times greater than the diameter of the conductor. Ebonite, derivatives of cellulose or polymers of the group of the polyvinyl compounds, such as, for instance, flexible polystyrene are preferably employed as mechanically 35 resistant insulating materials for the spacer winding. Directly over the spacer winding 41 is arranged the screen or return conductor 42 designed in the form of a wire braid. The sheath 43 of insulating material which consists 40 preferably of rubber or of any other suitable artificial material, for instance, of mixed polymers of vinyl chloride and ester of acrylic acid, serves as an outer protection. The closed sheath 45 43 of insulating material may be metallized, for instance, with pulverized aluminum. In this manner the conductor is provided with a surface having a metallic luster so that in the event of rays of light striking the conductor the same 50 are easily reflected and therefore cannot unfavorably affect the protective sheath.

Fig. 5 shows another embodiment in which the conductor is surrounded with two self-supporting 55 spacer windings arranged one over the other. 50 is the conductor around which are wound the two spacer windings 51 and 52. The latter may in some cases be made of different insulating materials; for instance, the spacer winding 51 of polystyrene or the like and the spacer winding 60 52 of ebonite or the like. Over the spacer winding 52 are arranged in succession the metallic screen or outer conductor 53, a fiber covering 54 and a layer of varnish 55, for instance, aluminum 65 varnish.

According to the embodiments shown in Figs. 6 and 7 an insulation sleeve is also arranged between the air-space insulation and the screen. In both figures the same parts are denoted by similar reference characters. The inner conductor 70 60 may either be made of tinned or zinc-coated steel wire or of aluminum wire so that the use of a copper wire is not absolutely necessary. A helix 62 of artificial substance, for instance, of polystyrene (particularly in a stretched state) 75

surrounds the conductor 60 in spaced relation thereto. The helix may be designed in such a manner as to be stretched to a greater or smaller extent than is shown in the drawing. Around 5 the helix is arranged a sheath of artificial substance either in the form of a closed sleeve 63 as shown in Fig. 6 or a sleeve formed by a band winding 64 as shown in Fig. 7. As material for the sleeve 63 particularly an artificial substance 10 is employed capable of being sprayed, for instance, consisting of mixed polymers of vinyl compounds or of other hydrocarbons, whereas in the case of the sleeve 64 an artificial substance 15 is employed capable of being worked into a ribbon or foil and consisting, for instance, of cellulose derivates repelling water or afterchlorinated polyvinyl chlorides or the like. Over this sleeve 63 or 64 is arranged a more or less fine-meshed metal covering 65 which may consist of 20 the same materials as those already mentioned for the inner conductor. As an outer covering a closed sheath 66 of artificial substance as in Fig. 6 or a sheath 67 of textile fabric as in Fig. 7 may be arranged over the metal covering 25 65, which textile fabric may consist of one or more layers of artificial materials or artificial fibrous materials and which is particularly to be varnished. The purpose of this sheath 66 or 67 is to protect the conductor as a whole against 30 tacks by oils, operating or motive fluids and the like or against corrosion. It is also possible to use structural parts of the one embodiment in the other embodiment; for instance, to interchange the sheaths 63 and 64 with one another. Also 35 other dimensions may be used instead of those shown; for instance, the sleeve 64 may consist of several windings whose lap joints are displaced with respect to one another.

The figures show the invention as applied to 40 high-frequency cables with a single concentric or screened conductor. The invention may obviously also be applied to high-frequency cables with several concentric or screened conductors.

What is claimed is:

45 1. An air-space insulated cable, including in combination a conducting sheath, a conductor within said sheath, and at least one open-wound self-supporting spacing helix, formed by a strand element of insulating material, surrounding the inner conductor and disposed within said conducting sheath, the inner diameter of said helix being at least 50% greater than the diameter of 50 said inner conductor, and the latter being disposed in the helix to have freedom of movement therein.

55 2. An air-space insulated cable, including in combination a conducting sheath, a conductor within said sheath, and at least one open-wound spacing helix formed of a strand element, said helix surrounding the inner conductor and disposed within said conducting sheath, said strand element consisting of a solid, mechanically resistive insulating material to render said helix self-supporting, the inner diameter of said helix being at least 50% greater than the diameter of 60 said inner conductor, and the latter being disposed in the helix to have freedom of movement therein.

65 3. An air-space insulated cable, including in

combination a conducting sheath, a conductor within said sheath, an open-wound self-supporting helix consisting of an insulating material strand element and surrounding the inner conductor and disposed within said conducting sheath, the inner diameter of said helix being at least 50% greater than the diameter of said inner conductor, and the latter being disposed in the helix to have freedom of movement therein, and a second strand element of insulating material wound in an open helix around the first helix and suitably spaced therefrom. 10

4. An air-space insulated cable, including in combination a conducting sheath, a conductor within said sheath, an open-wound self-supporting helix consisting of an insulating material strand element and surrounding the inner conductor and disposed within said conducting sheath, the inner diameter of said helix being at least 50% greater than the diameter of said inner conductor, and the latter being disposed in the helix to have freedom of movement therein, a second strand element of insulating material wound in an open helix around the first helix and suitably spaced therefrom, and a closed band winding of insulating material disposed between 15 said two helical windings. 20

5. An air-space insulated cable, including in combination a conducting sheath, a conductor within said sheath, and at least one open-wound self-supporting spacing helix, formed by a strand element of insulating material, surrounding the inner conductor and disposed within said conducting sheath, the inner diameter of said helix being several times greater than the diameter 30 of said inner conductor, and the latter being disposed in the helix to have freedom of movement therein, said insulating material consisting of a flexible polyvinyl compound. 35

6. An air-space insulated cable including in combination a highly flexible conducting sheath, a conductor within said sheath, and at least one open-wound self-supporting spacing helix, formed by a strand element of insulating material, surrounding the inner conductor and disposed within said conducting sheath, the inner diameter of said helix being several times greater than the diameter of said inner conductor, and the latter being disposed in the helix to have 40 freedom of movement therein. 45

7. An air-space insulated cable, including in combination a highly flexible conducting sheath, a conductor within said sheath, and at least one open-wound self-supporting spacing helix, formed by a strand element of insulating material, surrounding the inner conductor and disposed within said conducting sheath, the inner diameter of said helix being at least 50% greater than the diameter of said inner conductor, and the latter being disposed in the helix to have 50 freedom of movement therein, and a highly flexible closed sheath of insulating material disposed between said conducting sheath and said spacing helix. 55
